(57) **CLAIM**

The ornamental design for a Connector Element, as shown and described.

DESCRIPTION

FIG. 1 is a first perspective view of a connector element; FIG. 2 is a second perspective view of the connector element shown in FIG. 1;

FIG. 3 is a bottom view of the connector element of FIGS. 1 and 2;

FIG. 4 is a front view of the connector element of FIGS. 1 and 2;

FIG. 5 is a lateral view of the connector element of FIGS. 1 and 2;

FIG. 6 is a back view of the connector element of FIGS. 1 and 2;

FIG. 7 is a top view of the connector element of FIGS. 1 and 2;

FIG. 8 is a first perspective view of the connector element of FIGS. 1 and 2 shown in an environmental use; and FIG. 9 is a second perspective view of the connector element of FIGS. 1 and 2 shown in an environment use.

The broken lines in the figures depict environmental subject matter that forms no part of the claimed design.
